PIANO ATTACHMENT

Martin Rothman, 2895 Grand Concourse, and Irving Bernstein, 1240 Walton Ave., both of Bronx, N.Y.

Filed May 13, 1958, Ser. No. 734,938

2 Claims. (Cl. 84—224)

This invention relates to a piano attachment and more particularly to a device for modifying the normal tone of the piano.

It has been known in the past to provide a piano attachment wherein a tone changing, or a muffling device is optionally interposed between the hammers of the piano and the strings. When muffling was desired, the device comprised a fabric strip, generally of felt or the like. When it was desired to provide different tone effects, the device comprised a flexible back having integral hanging strips at the ends of which were metallic buttons or the like which are struck by the hammer and which, in turn, struck the strings to produce a varying tone.

Devices of the above type have been objectionable in that they had to be specially formed and installed in a piano and, in any event, were incapable of satisfactory adjustment. In most cases, the installation was mechanical, expensive and was generally required to be done at the factory. In regard to the varying tone devices, once installed the inability to adjust the same became a problem because, whereas the hammers of a piano might shift due to warping or the like, the tone modifying strips above mentioned remained in their preset position so that the tone of the piano notes would not be varied uniformly and the device became therefore defective or even useless.

With the foregoing in mind, we have devised a piano attachment which may be simply installed in most pianos in use or as made today. Thus, we have devised the tone modifying or tone varying device in combination with a telescopic, spring controlled holder which may be simply set into position by engaging the opposing side walls of the piano. The spring action of the telescoping rods permits the device to be installed by simply depositing the rod in place. A particular advantage to be derived therefrom is the fact that the rod can thus be vertically or horizontally shifted as desired in order to further modify the tone produced. In other words, if the player wishes to produce different effects he can simply raise or lower or laterally adjust the tone changing device bodily so that the hammer strikes different portions of the hanging strips. This result has been impossible to achieve in prior devices which were preset in substantially one position.

A most important object of this invention is also the provision of hanging strips which are individually adjustable in accordance with the positioning or location of the hammers of any particular piano. Thus, our device permits installation of the device in any suitable piano, and also permits the strips to be shifted in accordance with the individual spacing of the hammers in any such piano, old or new. A most important advantage of such structure is that if the positions of the hammers shift due to aging and warping of the supporting structures, the individual strips of this invention may simply be shifted accordingly in order to meet the changed conditions. Thus, it will be recognized that our device not

2

only adapts the piano attachment for simple installation in most pianos but even improves an original installation in that the hanging strips can be shifted in accordance with structural changes in the piano pursuant to aging or the like.

The invention will be further understood from the following description and drawings in which:

Figure 1 is a fragmentary view of the upper portion of an upright piano with the front removed to expose 10 the upper portions of the strings, the tone modifying attachment being shown in position;

Figure 2 is an enlarged, cross-sectional view as taken along the line 2—2 of Figure 1;

Figure 3 is a schematic view illustrating the coaction 15 of the hammer and the tone modifying device in striking a piano string; and

Figure 4 is a view of the device when employed as a muffler.

Referring to Figures 1 to 3, the piano illustrated is 20 provided with side walls 10 and 11, as well as a top wall 12 which is generally hinged at the back to provide access to the interior of the piano. The eighty-eight notes of the piano are produced through strings 13 which are secured by conventional means to the piano back 14. 25 It will be understood that the piano construction per se is purely conventional including the inclination of some of the strings and arrangement of others in groups. A series of conventional felt hammers normally strike the strings 13 so as to produce the tones. Our attachment 30 is interposed between the series of hammers and the strings as will hereinafter be made clear.

The main body of our device comprises an elongated, collapsible and extensible rod. In the form shown, it 35 comprises a telescopic tube having a central section 15 and two telescoped end sections 16 and 17. End sections 16 and 17 may be solid or tubular. They are provided at their outer ends with tips or heads 18 of soft rubber or the like which are frictionally secured thereover.

Disposed within the respective ends of central section 40 15 are coil springs 19 which have their inner ends seated against or slightly coiled about stops 20. Stops 20 may simply be an annular collar indented in the body of the tube portion 15. End sections 16 and 17 are connected to and bear against the outer ends of springs 19 so that 45 said end sections are normally outwardly directed. The connection involves simply the hooking of the spring outer end into a hole in the end section so that the end section is prevented from flying outwardly pursuant to the spring action. When it is desired to install the 50 device in a piano, sections 16 and 17 are telescoped or collapsed inwardly against the action of springs 19 and the device is placed in position whereupon the end sections 16 and 17 will be urged outwardly by springs 19 into firm contact with the inner surfaces of side walls 55 10 and 11.

Suspended over tube sections 15, 16 and 17 are flexible strips 21 having metallic or otherwise rigid buttons 22 disposed at the free, lower ends thereof. Strips 21 may be of fabric such as canvas, or may be of cotton fabric coated with rubber. The strips are formed with a circular or annular top portion designed to embrace and effect firm frictional contact with tube sections 15-17, although slidable thereon to permit horizontal adjustment. A clip 23, which may be an ordinary staple, 60 serves to determine the size of the top, circular end of strip 21. Strip 21 further comprises a downwardly depending arm 24 at the free end of which is secured the button 22. Button 22 may be a metal clip folded around the lower end of the strip as is well known.

The device is employed by threading the strips 21, usually eighty-eight of them, over the three tube sections 65 15-17 and simply installing the tube sections between

side walls 10 and 11 as above set forth. Buttons 22 will be interposed between the piano hammers 25 and the strings 13 as illustrated in Figure 3. Each piano hammer 25 must strike one of the strips 21, in most cases exactly broadside. Accordingly, the strips 21 are individually horizontally shifted until each one is in correct position relative to each of the hammers 25. The individual strips 21 permit such adjustment regardless of the individual variations in the hammers of different pianos. Further, if a hammer varies in spacing, by accident or aging, the strips can nevertheless be easily shifted to meet any such conditions. The strips, through their frictional engagement with the tube sections 15 to 17 will remain in any set position. The action of the hammers in striking the buttons have substantially no effect upon the positioning 15 of the strips because the depending portions 24 are very flexible and do not transmit forces from the button 22 to the upper circular portions. Accordingly, the strips will remain in their preset position.

It will be noted that the entire device can be shifted vertically in accordance with the arrows 26 (Figures 1 and 3). This is an important factor because a player might wish to vary the extent of coaction between the hammers 25 and the buttons 22. Thus he may prefer the entire buttons to be struck or only a portion thereof. The vertical variation is easily effected and the rod will remain as set due to the frictional engagement of the rubber heads 18 as urged outwardly by the springs 19. Furthermore, the device may be shifted horizontally as indicated by the arrows 27 to vary other factors such as the amplitude and the tone. In addition, the strips can be shifted to strike less than all of the group of strings constituting a note for further varying the effects.

It can be seen from the foregoing that our device not only makes possible the use of the attachment in substantially all upright or similar piano with the utmost simplicity of installation but improves the results secured as a whole regardless of such simplicity.

In Figure 4 we show how the tube sections 15-17 may be used with a tone muffler 28. Muffler 28 has a top tubular portion encircling the tubes and a depending portion which is interposed between the hammers and the strings just as are the flexible strips. Muffler 28 has cut-outs 29 in order to accommodate structural formations (the cross-bar pins) in most pianos as will be recognized by those skilled in the art. The form of the muffler 28 is not, of itself, new. The spring-actuated, telescopic nature of the tube sections permit the simplified installation of the muffler with both horizontal and vertical adjustability in accordance with the player's desire. Further, our device makes the muffler 28 easily replaceable since it need merely be threaded over the rod.

As examples of desirable dimensions, but without any limitations of this invention, we point out that a suitable dimension for the central section 15 of the rod is 50 inches while the end sections may be 10 inches. Collars or stops

5 20 may be 13½ inches from the ends of section 15 and the normal length of springs 19 may be 13 inches. It is also feasible, as will be obvious, to divide section 15 into two sections of 25 inches each, this expedient being useful in facilitating transportation or shipping.

We have shown what are considered to be preferred embodiments of our invention but it is obvious that numerous changes and omissions may be made without departing from its spirit.

What is claimed is:

1. A piano attachment for use in a piano having two opposing side walls, said attachment comprising an elongated composite, tubular rod formed from a plurality of tubular sections, spring means enclosed within at least one section and acting on a succeeding section for normally longitudinally extending said sections relative to each other, frictional engaging heads secured to the respective outer ends of the composite rod whereby the rod may be suspended pursuant to said spring means between said two opposing side walls, a plurality of individual flexible strips suspended from said rod and rigid buttons disposed on the lower ends of said strips, said buttons being adapted to be interposed between the hammers and the strings of a piano, each of said strips being individually horizontally adjustable on said rod, said strips being formed with annular top portions which frictionally embrace the rod and are slidable thereon.

2. The combination with an upright piano having an upper string and hammer section within opposing side walls of the piano, of a tone modifying attachment, said attachment comprising a collapsible and extensible elongated rod, spring means acting on said rod for normally extending it longitudinally, frictional engaging heads on the respective ends of said rod frictionally suspending the 30 rod from said opposing side walls, and tone modifying means suspended from said rod and disposed between the strings and the hammers of said piano section, said rod being freely movable along said side walls to vary the position of said tone modifying means, said tone modifying 35 means comprising individual flexible strips each independently slidable over said rod for horizontal adjustment thereon and adapted to be interposed between each hammer and associated string, said strips being formed with annular top portions which frictionally engage said rod.
